CLAIM

The ornamental design for a organizer panel, as shown and described.

DESCRIPTION

FIG. 1 is a front elevational view of an organizer panel according to the invention;

FIG. 2 is a side elevational view thereof from the right side;

FIG. 3 is a back elevational view thereof;

FIG. 4 is a bottom plan view thereof, the top plan view being a mirror image; and,

FIG. 5 is a side elevational view thereof, from the side opposite FIG. 2.
